John P. Faber, Dunellen, N. J., assignor to The Muller Machinery Company, Inc., Metuchen, N. J., a corporation of New Jersey

Application May 23, 1955, Serial No. 36,161

Term of patent 14 years

(Cl. D14—3)

Fig. 1

Fig. 2

Fig. 1 is a perspective view of the front of a mortar mixer or similar article, showing my design.

Fig. 2 is a perspective view of the rear of the mortar mixer or similar article shown in Fig. 1.

The end view of the mixer taken from the left of Fig. 1 or the right of Fig. 2, is not shown because it is plain.

I claim:

The ornamental design for a mortar mixer or similar article, substantially as shown and described.
